UNITED STATES PATENT OFFICE

GEORGE J. MEUER, OF MILWAUKEE, WISCONSIN, ASSIGNOR TO CUTLER-HAMMER, INC.,
OF MILWAUKEE, WISCONSIN, A CORPORATION OF DELAWARE

DESIGN FOR AN ELECTRIC APPLIANCE PLUG

Application filed April 1, 1931. Serial No. 39,315. Term of patent 14 years.

To all whom it may concern:

Be it known that I, GEORGE J. MEUER, a citizen of the United States, residing at Milwaukee, in the county of Milwaukee and State of Wisconsin, have invented a new, original, and ornamental Design for an Electric Appliance Plug, of which the following is a specification, reference being had to the accompanying drawings, forming part thereof.

Figure 1 is a front elevational view of an electric appliance plug showing my new design.

Fig. 2 is a side elevational view of the plug shown in Fig. 1.

Fig. 3 is an end view of the plug.

Fig. 4 is a sectional view on line 4—4 of Fig. 1.

Fig. 5 is a perspective view of the plug.

I claim:

The ornamental design for an electric appliance plug, substantially as shown.

GEORGE J. MEUER.
